DRAFT EQUALIZER

Original Filed June 25, 1926

Inventor:

Guest Johnson

UNITED STATES PATENT OFFICE.

GUST JOHNSON, OF ORRIN, NORTH DAKOTA.

DRAFT EQUALIZER.

Application filed June 25, 1926, Serial No. 118,571. Renewed October 10, 1928.

This invention relates to draft equalizers and it is an object of the invention to provide a device of this kind especially designed for use in connection with an uneven number 5 of animals, preferably five, and wherein the construction of the device is such as to reduce side draft.

It is also an object of the invention to provide a device of this kind which is constructed and assembled in a manner whereby 10 it is possible to use five animals abreast in connection with a plow.

The invention consists in the details of construction and in the combination and 15 arrangement of the several parts of my improved draft equalizer whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the 25 better understood, I will now proceed to describe the same with reference to the accompanying drawings, wherein:

Figure 1 is a plan view illustrating a draft equalizer constructed in accordance with an 30 embodiment of my invention;

Figure 2 is an enlarged sectional view taken substantially on the line 2—2 of Figure 1, with certain of the parts in elevation;

Figure 3 is a view partly in section and 35 partly in elevation, the section being taken on the line 3—3 of Figure 1.

As herein embodied, M denotes the main equalizing or draft member which, as herein disclosed, comprises an elongated plate 1 of requisite thickness and which is returned upon itself, as particularly illustrated in Figure 2, to provide the upper and lower members between which is snugly engaged an elongated beam 2. This beam 40 2 extends from the free ends of the plate 1 to a desired point inwardly of the connected extremities of the upper and lower members whereby is provided an elongated opening or slot 3. The plate 1 and the beam 2 are maintained in desired assembled relation by the bolts 4, 5 and 6.

The opening or slot 3 is intersected by a bolt 7 in relatively close proximity to the connected extremities of the upper and lower members of the plate 1. Positioned

within the opening or slot 3 and rotatably mounted upon the bolt 7 is a pulley or roller 8.

The bolt 4 is spaced from the bolt 5 a distance equal to two-thirds of the distance 60 between said bolt 5 and the bolt 7.

The extremities of the bolt 5 above and below the member M have engaged therewith the clevis C of any preferred type.

The upper and lower faces of the beam 65 2 around the bolt 5 are provided with the substantially semi-circular recesses 9 which, in connection with the overlying portions of the members of the plate 1, provide pockets in which are received the inner end 70 portions of the forwardly directed arms 10, the portions of the arms 10 within the pockets being pivotally or freely engaged with the bolt 5 hereinbefore referred to.

The outer end portions of the arms 75 10 overlie the upper and lower faces of the supplemental draft or equalizing member S and are pivotally connected thereto by the bolt 11. The bolt 11 is positioned to one side of the longitudinal center of the 80 supplemental member S a distance necessary to assure the requisite equalizing of the draft.

At substantially its longitudinal center the member S has pivotally connected 85 thereto by the bolt 12 the forward end portions of the rigid pulling straps 14 which overlie the upper and lower faces of the member S. These straps 14 have their rear end portions overlying the upper and 90 lower faces of an auxiliary equalizing member A and pivotally connected thereto by the bolt 15. This member A is of requisite length and substantially U-shaped in form having its side plates overlying the adjacent 95 end portion of the member M and pivotally held thereto by the bolt 4. The inner or free extremities of the side plates of this member A are pivotally connected, as at 17, to the inner extremities of the rigid 100 draft straps 18. These draft straps 18 are of a length to terminate a desired distance in advance of the member S and said draft straps have operatively engaged with their outer extremities a singletree 19. In order 105 that the straps 18 will have requisite free swinging movement with respect to the member S, I find it of advantage to apply to the upper and lower faces of the member S the elongated brackets 20 with which the 110

straps 18 have contact and are thus maintained free of the bolts 11 and 12 and the arms 10 and straps 14.

The distance between the pivot bolts 15 and 4 is one-half of the distance between the bolt 4 and the pivotal connections 17, thereby permitting the auxiliary member A to equalize the draft from the singletree 19 and the pull on the straps 14.

10 The left extremity of the members, or that end portion similar to the end portion of the member M to which the member A is engaged, has disposed therethrough a bolt 21 which provides a pivotal mounting for the 15 forwardly directed straps 22 each of which in turn being pivotally connected, as at 23, with the central portion of a doubletree 24. The bolt 21 also provides a mounting for the rearwardly disposed elongated clevis 25 20 to which is attached an extremity of a chain 26.

This chain 26 extends around the pulley 8 hereinbefore referred to and also around the pulley 27 carried by the central portion 25 of the doubletree 28 and positioned rearwardly thereof.

The adjacent or right end portion of the member S has bolted thereto, as at 29, the side arms of a substantially U-shaped member B and the extremity of the member S between the side arms of such bracket is provided with a slot or kerf 30 intersected by the bolt 31 with which is engaged the adjacent extremity of the chain 26. This 35 bolt 31 is selectively disposed through a link of the chain 26 whereby the proper application of such chain is assured.

In view of the foregoing, it is believed it will be readily understood that I have provided a draft equalizer for use with five 40 horses working abreast whereby side draft is reduced and more particularly when the equalizer is being used in connection with a plow.

45 From the foregoing description it is thought to be obvious that a draft equalizer constructed in accordance with my invention is particularly well adapted for use by reason of the convenience and facility with 50 which it may be assembled and operated, and it will also be obvious that my invention is susceptible of some change and modification without departing from the principles and spirit thereof and for this reason 55 I do not wish to be understood as limiting myself to the precise arrangement and formation of the several parts herein shown in carrying out my invention in practice except as hereinafter claimed.

It is to be understood that the equalizer 60 as herein disclosed is an improvement on the type of equalizer shown in my pending application Serial No. 114,569 filed June 8, 1926, but in the present invention the structure is for five draft animals instead of four 65 as set forth in my other application.

I claim:

1. A draft equalizer comprising a main evener member, a supplemental evener member in advance thereof, arms pivotally connected with the intermediate portion of the main member and to the supplemental member at a point to one side of its longitudinal center, an auxiliary member pivotally connected with an end portion of the main member, pulling straps pivotally connected with the central portion of the supplemental member and also pivotally connected to one end of the auxiliary member, draft straps pivotally connected with the opposite end 75 portion of the auxiliary member and extending forwardly of the supplemental member, the space between the pivotal mounting of the auxiliary member and the pivotal connection between the pulling straps and said auxiliary member being substantially one-half of the distance between the pivotal mounting of the auxiliary member and the pivotal connection of the draft straps with the auxiliary member, a doubletree operatively engaged with the left side of the supplemental member, a pulley carried by the right side of the main member, a flexible member operatively connected with the left side of the supplemental member passing 85 around the pulley of the main member and secured to the right end of the supplemental member, and a second doubletree having a pulley around which the flexible member is directed.

2. A draft equalizer as defined in claim 1 wherein the distance between the pivotal connection of the arms with the main member and the mounting for the auxiliary member is substantially two-thirds of the distance between the pivotal connection of said arms with the main member and the mounting for the pulley of the main member.

3. A draft equalizer as defined in claim 1 wherein the draft straps overlie the upper 110 and lower faces of the supplemental member, and guard brackets carried by said upper and lower faces of the supplemental member with which the draft straps are adapted to contact.

In testimony whereof I hereunto affix my signature.

GUST JOHNSON.
